HIGH VACUUM, LOW TEMPERATURE
DRYING APPARATUS

John Reichel, Wynnewood, Pa., assignor to
Reichel Laboratories, Kimberton, Pa., a firm
composed of John Reichel and Hollis Wolsten-
holme

Application June 24, 1941, Serial No. 399,449

4 Claims. (Cl. 34—73)

In the preservation of sera, plasma, proteins or other substances for future use, it is necessary that the substances be as completely dried as possible, that this drying be uniform, that the physical structure—whether crystalline or amorphous—be not changed and that the chemical reactions be not interfered with, or, in the event that the product is a bacteriological culture or a virus or the like, its effectiveness be not in any way altered. The most recent and advanced method for accomplishing these objects consists in pre-freezing the material to be dried and then submitting the frozen mass to a high degree of vacuum in the presence of regulated heat, whereby the water of the frozen mass is sublimated while the mass is still at a temperature well below the freezing point.

My invention therefore relates to a novel self-contained, portable, high vacuum, low temperature drying apparatus which, I have found in actual practice, is capable of efficiently and expeditiously carrying out the objects briefly outlined above, it being understood that, while by way of illustration I refer to sera, plasma, proteins and similar substances, my apparatus is not limited to the drying of these substances only, but is equally applicable to the drying of other substances as well.

In my co-pending application Serial No. 386,878, filed April 4, 1941, entitled "High vacuum low temperature drying apparatus" there is disclosed a practical and efficient construction capable of attaining the objects outlined and it is therefore a further object of the present invention greatly to simplify the construction and to standardize the manufacture of the parts thereof in order greatly to reduce the cost of production and greatly to facilitate the assembly and manipulation of the apparatus by the operator in the field.

Still more specifically it is a further object of this invention to produce an extremely compact apparatus and one which can easily be assembled and packed for shipment.

A still further object is to make the component parts of my novel apparatus completely interchangeable as far as practicable so that, in the event of breakage, the parts can be replaced from standard stock without the necessity of special designs or special specifications.

Other features of construction and advantage of my novel apparatus will be more clearly understood from the following specification and the accompanying drawing which represents a vertical cross sectional view of an apparatus em-

bodying my invention, the drawing showing only the parts necessary sufficiently to illustrate the invention to enable it to be used by those skilled in the art.

Referring to the drawing in which like reference characters indicate like parts, 2 designates any suitable container or box the walls of which are suitably insulated against heat transmission. The box 2 is provided, in the top 4, with a suitable opening through which may be inserted the receptacle 6. The receptacle 6 may be made of glass, metal or any other desired substance, and is preferably dome or bell shaped. Within the box 2 is suitably secured the supporting ring 8 which is adapted to engage and support the receptacle 6. The inner rim of the ring 8 is preferably provided with the gasket 10 so as to form an airtight junction with the wall of the receptacle 6. Below the ring 8 is positioned a refrigerating coil 12 which is connected through the inlet 14 and the outlet 16 to a refrigerating mechanism not shown. Instead of the refrigerating coil 12 it is within the scope of my invention to utilize natural ice or frozen CO₂ which will be placed in the compartment 18. 20 designates a drain controlled by a suitable valve and through which moisture which may collect on the coil 12, or the water from the natural ice if the latter is used, or the vapor from the CO₂ if the latter is used, may be discharged. 22 designates a plate having the annular groove 24 in which is positioned the gasket 26. As seen from the drawing, the plate 22 is adapted to seat on the rim of the receptacle 6 to form a closure for the top thereof. The plate 22 is also provided with the fitting 28 which is controlled by the petcock 30. 32 designates a pipe secured to the plate 22 in an airtight manner and projecting therethrough as at 34 so as to extend within the receptacle 6 when the plate 22 is assembled as shown in the drawing. The pipe 32 is also controlled by the petcock 36 and is likewise secured to another plate 38 through which it extends as at 40. The plate 38 is also provided with the annular groove 42 which has the gasket 44 on which is adapted to seat the receptacle 46 which is identical with the receptacle 6 in shape and size. The plate 38 is also provided with a fitting 48 controlled by the petcock 50, the fitting 48 being identical with the fitting 28. The plates 22 and 38 are provided with the recesses 52 which are adapted to receive bottles or the like 54 containing the material to be treated. The receptacles 6 and 46 are provided with identical, combined pressure gage and handle 56.

The operation is as follows:

The box 2, with the refrigerating coil 12 or the frozen CO₂, or other refrigerating element such as natural ice, liquid air, brine or the like, is placed in position and then the receptacle 6 is mounted on the ring 8 as shown. The preassembled pipe 32 and upper and lower plates 38 and 22 are then placed in position, it being immaterial whether the plate 22 or the plate 38 seats upon the rim of the lower container 6. The upper container 46 is then seated in position as shown and the suction end 56 of the vacuum apparatus (not shown) is connected to the fitting 28 carried by and extending through the plate 22. It is of course understood that if the position is reversed so that the plate 38 rests upon the rim of the receptacle 6 the suction end 56 of the vacuum apparatus would be connected to the fitting 48. With the petcock 50 tightly closed and the petcocks 30 and 36 open, the suction apparatus is operated so as to create a vacuum within the container 6 and hence through the conduit 32 and within the upper receptacle 46. This serves to dry the contents of the bottles or the like 54 and, in order to prevent any moisture extracted from the contents of the bottles 54 from reaching the vacuum-creating apparatus, I provide the coil or other cooling medium 12 which causes the moisture content to condense in the receptacle 6. If it is desired to maintain the vacuum within the container 46 even after the suction apparatus is out of operation, it is merely necessary to close the petcock 36. Likewise, after the drying operation is completed and it is desired to remove the inverted container 46 from the upper plate 38, it is merely necessary to open the petcock 50 thereby allowing air to enter through the fitting 48. The plates 38 and 22 are preferably provided with heating elements as shown in my copending application above referred to so that whichever plate is serving to support the material to be dried, may be connected to a source of electrical energy in order to deliver controlled heat as may be desirable or necessary. Since this is shown in my copending application I deemed it unnecessary to illustrate it in detail in the present application, it being understood that I reserve the right, in the event that my copending application should for any reason not mature into a patent, to incorporate that feature in the present application.

It will thus be seen that by the present invention the entire apparatus consists of the two identical containers 6 and 46 which may be interchangeably used, the pipe 32 integrated with the upper and lower plates 22 and 38 which also has no upper or lower end, and the box 2 which serves as a support for the entire apparatus and which also contains the refrigerant. The advantage of a construction of this character will be readily appreciated when it is considered that an apparatus of this kind would be a necessity in the various encampments of our expanding national army and, for that matter, in proximity to or immediately behind the battle field itself where

haste is essential and where elaborate installations are impossible.

Having thus described my invention, what I claim as new and desire to secure by Letters Patent is:

1. A high vacuum, low temperature drying apparatus comprising a conduit, a pair of spaced plates carried thereby, a pair of identical open ended receptacles, the opposite faces of said plates being provided with identical grooves for engaging the rims of the open ends of said receptacles, fittings carried by the juxtaposed faces of said plates and adapted to be connected to a source of suction or to the atmosphere selectively and at will, and a refrigerating chamber adapted to enclose at least a portion of one of said receptacles.
2. A high vacuum, low temperature drying apparatus comprising a vertically disposed conduit, a pair of horizontally disposed spaced plates carried thereby, a pair of identical but oppositely disposed bell-shaped receptacles, the opposite faces of said plates being provided with identical annular grooves for engaging the corresponding shaped rims of said receptacles, fittings carried by the juxtaposed faces of said plates and adapted to be connected to a source of suction or to the atmosphere selectively and at will, and a refrigerating chamber for supporting and enclosing at least a portion of one of said receptacles.
3. A high vacuum, low temperature drying apparatus comprising a refrigerating chamber, a receptacle, means detachably for supporting said receptacle within said chamber, a plate having a groove on the lower face thereof adapted to engage the rim of said receptacle, a second plate having a groove on the upper face thereof, a second receptacle having its rim seated in said last mentioned groove, the grooves in said plates and the rims of said receptacles being identical for interchangeable engagement with each other, a conduit extending through said plates and establishing communication between said receptacles and means connecting the interior of either of said receptacles to a source of suction or to the atmosphere selectively and at will.
4. A high vacuum, low temperature drying apparatus comprising a refrigerating chamber, a lower receptacle adapted to serve as a condenser compartment, means for detachably supporting said receptacle within said refrigerating chamber, a lower supporting plate having a groove in the lower face thereof for engaging the rim of said receptacle, an upper supporting plate having a groove in the upper face thereof, an upper inverted receptacle adapted to serve as a drying chamber and having its rim seated in said groove in said upper plate, a valved conduit interconnecting said plates and establishing communication between the interiors of said upper and lower receptacles, said receptacles being identical and interchangeably usable, and means for connecting the interior of either of said receptacles to a source of suction or to the atmosphere and at will.

JOHN REICHEL.
